PITCHER.

No. 18,466.

Patented July 17, 1888.

UNITED STATES PATENT OFFICE.

LOUIS HINRICH, OF NEW YORK, N. Y.

DESIGN FOR A PITCHER.

SPECIFICATION forming part of Design No. 18,466, dated July 17, 1888.

Application filed June 6, 1888. Serial No. 276,271. Term of patent 7 years.

To all whom it may concern:

Be it known that I, LOUIS HINRICH, residing in the city of New York, county and State of New York, and a citizen of the United States, have invented and produced a new and original Design for Jugs or Water Pitchers, of which the following is a specification, reference being had to the accompanying drawing, forming part hereof.

10 The drawing shows in elevation my newly-designed jug or pitcher, a single view being deemed sufficient to fully illustrate the same.

15 The leading features of my design consist in a jug or pitcher having an enlarged base or body substantially globular in form and a contracted tubular neck, the body of the jug being provided with two separate series of grooves or depressions which extend from the top to the bottom thereof in opposite directions, one series of said grooves crossing the other, as shown, whereby the elevations a a a and b b b are formed.

20 A represents the body of the jug or pitcher, and B the neck, to which a handle, C, is attached. The body of the jug is traversed in 25 separate directions by deep grooves or depressions D D, which extend from the top to the bottom thereof, whereby the diamond-shaped elevations a a a and the elevations b b b are formed on the surface of the body of the jug. 30 The grooves or depressions D D are curved, as shown, and at the point where they cross may be formed small knobs or button-shaped elevations c c c, which add to the ornamentation and increase the artistic effect. 35

Having fully illustrated and described my new and improved design, I claim and desire to secure by Letters Patent—

35 A design for jugs or pitchers having the form and surface configuration herein shown 40 and described.

LOUIS HINRICH.
